UNITED STATES PATENT OFFICE.

SAMUEL DE GRAZIA, OF WASHINGTON, DISTRICT OF COLUMBIA.

RUBBER HEEL.

1,398,631.

Specification of Letters Patent. Patented Nov. 29, 1921.

Application filed October 22, 1920. Serial No. 418,679.

To all whom it may concern:

Be it known that I, SAMUEL DE GRAZIA, a subject of the King of Italy, residing at Washington, in the District of Columbia, 5 have invented certain new and useful Improvements in Rubber Heels, of which the following is a specification.

This invention relates to certain new and useful improvements in rubber heels for 10 boots and shoes. In devices of this kind as usually constructed, metal washers are embedded within the body of the heel so as to form an abutment for the head of the nails used in securing the heel to the shoe. It is 15 found in practice, however, that these washers frequently cut through the rubber body of the heel and destroy the latter.

The principal object of the present invention is to provide a form of rubber or 20 cushion heel in which the metallic washers are dispensed with without sacrificing the durability of the article.

Further objects of the invention are generally to improve and simplify the construction of rubber heels as well as to decrease 25 the expense attending their manufacture and to render them more durable in use.

With the foregoing and other objects in view which will appear as the description 30 proceeds, the invention resides in the combination and arrangement of parts and in the details of construction hereinafter described and claimed, it being understood that changes in the precise embodiment of 35 the invention herein disclosed can be made without departing from the spirit of the invention as claimed and without sacrificing any of its advantages.

In the accompanying drawing forming a 40 part of this specification and wherein like reference characters indicate corresponding parts throughout the several views,

Figure 1 is a fragmentary view of a portion of a shoe provided with a heel constructed in accordance with the present invention, the heel being shown partly in section and partly in elevation,

Fig. 2 is a top plan view of the insert of the heel,

Fig. 3 is a longitudinal sectional view 50 thereof and taken upon line III—III of Fig. 2,

Fig. 4 is a bottom plan view of the heel shown in Fig. 1,

Fig. 5 is a view somewhat similar to Fig. 1 showing a modified embodiment of the

invention as employed with women's shoes, and

Fig. 6 is a top plan view of the insert 60 employed in the heel of Fig. 5.

The heel of the present invention consists of a rubber body portion with an insert preferably of leather embedded therein, the insert being nearer to the upper side of the heel than the lower side thereof and being 65 entirely covered by the body portion except at its marginal edge so as to give the appearance of a separate leather lever or lift, the heel being provided with nail holes which preferably extend through the outer or 70 thicker portion of the rubber body and terminate at the outer surface of the insert.

Referring more in detail to the drawing, the reference numeral 5 indicates the body portion of the heel, said body portion being 75 preferably formed of resilient rubber and having embedded therein an insert or reinforcement 6 formed preferably of leather. The insert 6 is preferably in the form of a plate corresponding in shape and size to the 80 body 5 in plan and having a large central opening 7 as well as numerous smaller openings or perforations 8 so as to allow the resilient rubber to flow through and firmly anchor the insert to the body portion for making 85 the two practically a homogeneous structure. It has heretofore been proposed to construct heels substantially the same as thus far described, but the resultant article was found to be of insufficient durability to 90 withstand the strains and wear and tear incident to its use because of the fact that separation of the body portion from the insert took place in a very short time. In order to guard against this objectionable 95 feature and to provide a heel which will meet with all of the requirements for a successful commercial use, I bevel the upper surface of the insert 6 inwardly as at 9 so

as to form the insert of tapered shape in 100 cross section as shown in Fig. 3 with the thinner edge of the insert forming the wall of the opening 7. The insert 6 may thus be considered a belt like member with a concavo spherical upper surface. This concav- 105 ing of the upper surface of the insert 6 permits the rubber of the body portion 5 to flow onto the upper surface of said insert as indicated at 10 in Fig. 1 and to unite with the rubber which extends through the openings 8, thereby firmly retaining the insert 110 against detachment. The portion 10 of the

body portion 5 is of tapered form and has its upper surface perfectly flat and in the same horizontal plane with the highest portion of the insert 6 so as to provide a continuous contact between the heel and the usual strip 11 of the shoe 12.

As shown particularly in Fig. 1, the coating of resilient rubber is very much thicker on the underside of the insert than on the 10 upper side thereof. The nail holes 13 through which the usual nails 14 are inserted extend through the thick end portion of the resilient rubber body and preferably terminate at the outer or under face 15 of the insert, the nails 14 being driven through the insert and the portion 10 into the member 11 in the usual way for securing the heel to the shoe. It is to be understood that the insert may be made of hard rubber 20 or other semi-flexible material having wear and strain resisting qualities of leather and capable of being used without interfering with the action of the heel or presenting such unyielding resistance as would cause 25 it to wear through in the same manner as the metallic washers. The resilient rubber portion and the insert are vulcanized so as to form in effect a unitary heel.

If desired the body portion 5 may be 30 formed with a continuous marginal rib 15 on its tread surface for anti-slipping purposes with the nail holes 13 extending therethrough as shown clearly in Figs. 1 and 4. It is found in practice that the heel of the 35 present invention is strong, simple, durable and inexpensive in construction as well as thoroughly efficient and practical in use and provides a finished appearance for the shoe with which it is used. The modified construction of heel shown in Figs. 5 and 6 is 40 substantially the same as the form shown in Figs. 1 to 4 inclusive with the exception that the body portion 5' is not provided with a rib upon its tread surface and is specifically 45 formed of such size and shape to be practically employed upon such small heels as are

commonly found upon women's foot wear. This form of the invention provides the nail holes 13' for the nails 14', and the insert 6' embedded in the body portion 5'. The 50 insert 6' is provided with the central opening 7' and perforations 8' similar to the insert of Figs. 2 and 3.

What is claimed as new is:—

1. A cushion shoe heel comprising a nail 55 holding insert in the form of a leather plate of the thickness of a lift at its margin and having a concavity in its upper face, said plate being provided with a central opening, and a rubber body in which the insert 60 is inclosed completely with the exception of its marginal edge, the rubber body extending through the opening of the insert and filling the concavity of the latter, the upper surface of the body being in the same plane 65 as the highest marginal portion of the insert, whereby the insert has the appearance of an upper leather lift when the heel is in use.

2. A cushion shoe heel comprising a nail 70 holding insert in the form of a leather plate of the thickness of a lift at its margin and having a concavity in its upper face, said insert having a relatively large central opening, and a rubber body in which the insert 75 is inclosed completely with the exception of its marginal edge, the rubber body extending through the central opening of the insert and filling the concavity of the latter, the upper surface of the body being in the same 80 plane as the highest portion of the insert, whereby the insert has the appearance of an upper leather lift when the heel is in use, said insert being provided with numerous relatively small perforations entirely around the 85 central opening thereof and through which the rubber of the body passes for integrally uniting the portions of said body which contact the upper and lower faces of the insert.

In testimony whereof I affix my signature. 90

SAMUEL DE GRAZIA.
